UNITED STATES PATENT OFFICE.

CARL A. MEILICKE, OF CHICAGO, ILLINOIS.

CARD-INDEX.

1,149,384.

Specification of Letters Patent. Patented Aug. 10, 1915.

Application filed August 22, 1914. Serial No. 358,060.

To all whom it may concern:

Be it known that I, CARL A. MEILICKE, a subject of the King of Great Britain, residing at Chicago, in the county of Cook and State of Illinois, have invented certain new and useful Improvements in Card-Indexes, of which the following is a specification.

My invention relates to improvements in loose-leaf card-indexes and the like; the particular structure shown as an exemplification of my invention being an express-rate index or calculator.

It will be apparent that information as to express rates from a given center—say Chicago—to all points in the United States 15 reachable by express, constitutes a volume of data that will be changed only rarely, as when new express stations are created or rates are changed. A compilation of such 20 information may therefore conveniently be in printed form and although the individual units, or leaves, bearing data should be removable, for replacement whenever occasion may require, the compilation is, in a sense, 25 a permanency, and its ordinary use from day to day does not involve bodily displacement of any of its parts. Similar conditions, in 30 general, are met with in many other compilations of data and information, and it is 35 particularly with reference to loose leaf devices for such use that my invention, in some of its aspects, has to do. It will, however, be apparent that in many features my invention is usable for other purposes, as 40 in the keeping of book entries of small accounts, and the like.

The general object of my invention is to 45 provide a simple, durable, efficient apparatus adapted for facile and rapid manipulation and indexed to give ready access to the desired appropriate card, and further objects of my invention will become apparent from the following description taken in conjunction with the accompanying drawings, in which—

Figure 1 is a perspective view of a structure embodying my invention with parts of its loose leaves removed. Fig. 2 is a side elevation of the same, with a fragment in section; Fig. 3 is a plan view showing the structure in use; Figs. 4 and 5 are enlarged fragmentary detail sections on lines 4—4

and 5—5 of Fig. 1. Fig. 6 is an enlarged cross section of fragments of the individual leaf; Fig. 7 is a horizontal section on line 55 7—7 of Fig. 2; Figs. 8 and 9 are front and rear views of individual leaves.

The collected printed data is displayed, or the receptive surfaces for reception of notations are presented on leaves 10, either 60 on the front or rear surface thereof, or on both. Each of these leaves consists of a stub 11 and a stiff card 12 connected by a flexible fabric hinge 13. To form such structure I make the leaf-sheets of three thicknesses, (Fig. 6) the center layer *a* being fabric, such as linen, and front and back facings *b* and *b'* being paper, pasted thereon. To secure the desired hinging flexibility the two paper facings are interrupted as at 13, 70 leaving only the fabric along the narrow hinge line; this being preferably accomplished in practice by grinding or cutting away the paper in opposite grooves *c* that extend down to the fabric on the hinge line. 75 Between the stubs 11 of the successive leaves I arrange spacers 11^a, each preferably about the thickness of one of the card stubs so that each data-bearing card may readily be moved through an arc of about 90 degrees 80 without interference from the adjoining cards. Such construction gives each stiff card freedom to open, unaffected by any other cards and without any resiliency that would tend to move any card so that the 85 card-volume may be opened at any point from its front leaf to its back leaf and will stand quiescent with its cards fully open at the desired point to the extent of about a 90 degree angle, so giving perfect uniformity of reading conditions and freedom from 90 liability to losing the desired place. To provide these spacers, I preferably form them integral with the leaf-stubs, grooving the sheets as at *c'* between stub 11 and spacer 11^a so that the stub and spacer may be folded flat, face to face. If a substantially flat-opening leaf is desired I add another spacer 11^b in the same way, as shown in Fig. 6. These cards 10, are mounted in a frame 16 100 which may be rectangular frame border of iron having side rails 17 with bottom flanges 18 extending inwardly therefrom and front and rear end rails 19 and 20 that have simi-

lar flanges. This frame is preferably mounted to stand at an oblique angle to the horizontal, having short legs 21 adjacent its front rail and longer legs 22 adjacent its 5 rear rail.

Where the device is to be used to receive written notes I increase the angular pitch of the frame, and make the cards to open down substantially horizontal, but for an index 10 such as an express rate index I regard the 90 degree opening and slighter pitch as preferable. The leaf stubs and spacers rest on the flanges 18 at their sides and, for retention in the frame each stub and spacer 15 has in its stub an opening 23 intersecting a narrow slot 24 that leads to the bottom edge of the stub. A locking bar 25 is mounted in the frame to engage these openings, said bar having a cylindrical bearing end 26 20 engaging and bearing in the front rail 19, and the flattened bar engaging in a suitable circular opening 27 in the rear rail 20. Obviously the flat extremity of the bar in the round opening 27 may be engaged by a key 25 so that the bar may be turned to vertical position as indicated in dotted lines in Fig. 8 to permit the removal of any card or cards, each with its attached spacer or spacers, or it may be turned to the position shown in 30 full lines in Fig. 8, to hold all of the stubs and spacers in place. To compress the stubs to hold them tightly in place, they are engaged, preferably at the rear end of the frame, by a follower strip 30 that fits between the side rails and bears on the side flanges 18, said follower having a wing 31 35 extending above the frame and tilted back beyond right angles to the plane thereof so as to form a back rest for the cards preferably arranged at about 30 degrees from vertical. Screws 32 taking through apertures in the rear rail 20 enable said follower to be adjusted forward so as to compress the stubs against the front rail 19, which preferably 40 is provided with a low stud 34 suitably arranged at an angle, preferably at about 90 degrees to the back rest 31 and against which the cards may drop as a front stop. A thick cover card 10^a, made especially stiff, 45 may be used as a frontmost member of the card-set, acting when thrown forward against stop 34 as a front rest or platform for the cards.

The cards are preferably provided with 50 individual index tabs 40, arranged so that successive tabs of each group or order partially overlap each other, the first tab being close to the left end of the card, or the area thereof allotted to the tabs, the next tab being a little farther toward the right and so on, with the next order of tabs beginning, as the particular layout of the system may require, at a point sufficiently spaced lengthwise of the index so that the entire first tab 55 thereof may be readily seen. It is fre-

quently necessary that a number of cards relating to the same general index heading shall be specifically sub-indexed; and I prefer that where practicable, each general heading shall begin a new order. On both 70 the front and rear surface of each tab I prefer that there shall be a note of the common heading as at 41, and a note of the specific sub-index heading as at 42, the first-mentioned general heading being on the portion of the tab which is covered by the tab of the adjoining card nearer to the eye of the reader, and the sub-index information being displayed beyond said nearer-the-eye tab. Thus, as best indicated in Figs. 8 and 75 9, where the State index "Cal." (for California) indicated at 41 is the general index mark and the sub-index "Ke" is indicated at 42, said sub index mark is given at the right on the front face of the tab and at the 80 left on the rear face of the tab. On the back of the tab, and on the card, all markings are upside down. This because, as best shown in Fig. 3, when the index is opened in the middle the general index mark of 85 90 the order of tabs can always be read on the card immediately opened and the specific index marks 42 of other sub-headings of that order will appear reading to the right on the cards that have not been opened and 95 to the left on the cards that have been opened. Thus the user may run forward or backward through the index with equal facility, the approximately-90-degree opening of the cards and the sloping of the index 100 frame effectively presenting at all times both the front face of one card and the reverse face of the preceding card. In this way I am enabled to use both faces of the card for display of data.

In the specific exemplification shown, where both card-faces are so to be utilized, I may utilize opposite faces for different associated purposes; and to this end I double-index the cards, and provide a second 105 tab 40' on each card that has data on its back. The tabs 40 are all arranged on the left half of their cards, tabs 40' on the right half. Particularly I may display on the front face of each card a list of express 110 stations, and in designated columns 45, 46, 47 and 48 I may display respectively an abbreviated indication of the company or companies serving that station; the express rate per hundred; a scale number; and the parcels-post zone. The scale number will refer to a scale on which the exact expressage on any weight less than 100 lbs. is displayed, and a set of these scales (which in the matter of express rates will number nearly 300) may 115 be displayed on the backs of the cards, so that the respective tabs 40' at the right of the cards may bear sequential scale numbers 42' in orders of ten, and also, for convenience, the 100-lb. rate, at 41'. As shown 120 125 130

in Fig. 9, each scale gives the rate pound by pound from one to a hundred. Thus to find the express rate on a certain number of pounds to any station reachable by express

5 it is only necessary to turn only to the name of that station, note the scale number printed opposite the name of the station, turn to the corresponding scale printed on the back of some card of the set, and the rate for the 10 precise number of pounds is there indicated.

While I have herein described in considerable detail the arrangement of data particularly useful in determining express rates, it will be apparent that the same concept 15 may be embodied for the display or notation of widely different data or information; and that in its other mechanical features my invention may be used for different purposes. I do not desire therefore 20 to be understood as limiting my invention to the particular use I have described by way of full illustration of one utilization thereof, further than specified in the claims.

Having described my invention, what I 25 claim is:

1. In a removable-leaf index, the combination of a frame, leaves each comprising a stub portion and a card portion, both consisting of a central ply of fabric and surface plies of paper, said stub and card connected by a hinged portion of the fabric only, spacer stubs between adjoining leaf stubs, and means for clamping the stubs in the 30 frame.

35 2. In a loose-leaf index, the combination of a border frame, leaves therein, each comprising a stub and card consisting of a central ply of fabric and surface plies of paper, said stub and card united by a hinge of 40 said fabric alone; spacers between the leaf stubs each substantially equal in thickness to a leaf stub, and means for holding said stubs in the frame.

3. In a loose-leaf index, the combination 45 of a border frame, leaves therein, each comprising a stub and card consisting of a central ply of fabric and surface plies of paper, said stub and card united by a hinge of said fabric alone; spacers between the leaf 50 stubs each spacer being of substantially the same size as a leaf-stub, and hingedly connected thereto.

4. In a loose-leaf index, the combination 55 of sheets, each comprising a stub, a hinge, and a leaf connected with said stub by said hinge, of a frame enveloping said stubs, a follower parallel with one end of said frame, and pressure screws extending through said frame and acting on said follower to compress the stubs.

5. In a loose-leaf index, the combination 60 of a rectangular frame, having bottom flanges at its sides, a plurality of sheets each comprising a stub of substantially the depth of said frame, a card and an attenuated

hinge connecting said card and stub; each said stub having therein a buttonhole slot; a flattened lock-bar mounted in the frame for rotation therein and engaging the button-hole slots; a follower interposed between one end-stub and an end-rail of the frame, and pressure screws taking through 70 said frame rail acting on said follower.

6. In a loose-leaf index, the combination 75 of a rectangular frame, having bottom flanges at its sides, a plurality of sheets each comprising a stub of substantially the depth of said frame, a card and an attenuated hinge connecting said card and stub; each said stub having therein a button-hole slot; a flattened lock-bar mounted in the frame for rotation therein and engaging the button-hole slots; a follower interposed between one end-stub and an end-rail of the frame, and pressure screws taking through 80 said frame rail acting on said follower, said follower having a wing extension extending above the frame inclined at an acute angle to the plane of the frame, and said frame at its other end having a 85 stop inclined at an angle of about 90 degrees to said wing.

7. In a removable leaf index, the combination 90 of a frame, a plurality of relatively stiff sheets mounted therein, each comprising a stub in the frame, a data bearing card and a connecting attenuated hinge, spacer stubs between the sheet stubs and hingedly connected thereto; means associated with the frame for clamping said stubs; stops 95 associated with the frame for limiting the card movement to approximately 90 degrees; said cards bearing data on opposite faces thereof, and having tabs partly overlapping each other when viewed either forwardly or backwardly, and similar index data printed on opposite faces of each tab at respectively opposite ends that are visible accordingly as the card is viewed from the front or from the back.

8. A sheet for a card index comprising a card portion and a stub portion hinge connected, said card portion bearing an index tab provided on each face with a general indication and a specific indication, said indications being transposed in transverse position and reversed in reading position on opposite faces of the tab.

9. A sheet for a card index comprising a veneered structure consisting of a central fabric, paper facings on both sides thereof, said paper cut away along a hinge line connecting the card-portion and stub-portion of said sheet, said card portion bearing an index tab provided on each face with a general indication and a specific indication, said indications being transposed in transverse position and reversed in reading position on opposite faces of the tab.

10. A sheet for a card index comprising 130

a central fabric and paper facings, said facings cut away on a plurality of parallel lines leaving fabric hinges, and dividing the sheet into a card and a plurality of hingedly connected stubs, said stubs being of substantially equal width.

In testimony whereof I hereunto set my

hand in the presence of two subscribing witnesses.

CARL A. MEILICKE.

In the presence of—

FORÉE BAIN,

MARY F. ALLEN.
